UNITED STATES PATENT OFFICE.

STILLMAN A. WEST, OF ST. LOUIS, MISSOURI.

METHOD OF STAYING BUTTON-HOLES.

SPECIFICATION forming part of Letters Patent No. 373,507, dated November 22, 1887.

Application filed May 10, 1886. Serial No. 201,768. (No model.)

To all whom it may concern:

Be it known that I, STILLMAN A. WEST, of the city of St. Louis, in the State of Missouri, have invented a certain new and useful Improvement in the Method of Staying Button-Holes, of which the following is a full, clear, and exact description, reference being had to the accompanying drawings, forming part of this specification, and in which—

10 Figure 1 is a perspective view showing one side of a number of pieces of shoe or other leather provided with button-holes, and illustrating my improved method of staying the holes. Fig. 2 is a similar view of the other side of a number of pieces of shoe or other leather. Fig. 3 is a perspective view of a piece of material, showing a series of worked button holes stayed according to my invention, and Fig. 4 is an under side view of the same.

20 My invention has for its object to provide an improved method of staying button-holes of boots or shoes and like articles.

25 My invention consists in the improved method hereinafter fully described, and pointed out in the claim.

Referring to the drawings, A represents a piece of shoe or other leather provided with a number of button-holes, B, which are worked in the usual manner. My invention relates 30 to an improved method of staying these button-holes, and in carrying it out I first pass a loop, C, of the thread D up through the material, as shown on the sections numbered 1, at a point one side of and near the button-hole. I next bend the thread over and pass the loop down through the material at the other side of and near said hole, as shewn on sections numbered 2. The next and last step is to pass the thread D of which the loop is made 35 through the loop, as shown in sections numbered 3, and the thread is drawn with suffi-

cient force to pull out the loop, but its passage through the material is prevented by the thread which was passed through it, as stated, and as shown in the section marked 4, Fig. 2. 45 This completes the stay, the appearance of it on the under or inner side of the shoe being as represented on section 4, Fig. 2, and the appearance on the upper or outside of the shoe being as shown on section 4, Fig. 1. 50 When one stay has thus been formed, the thread is passed to the next button-hole, and there the operation is repeated, and so on, a series of button-holes so stayed being illustrated in Figs. 3 and 4.

55 This method forms a secure and strong stay and can be practiced either by hand or by a suitably-constructed machine.

It is possible that the loop might be passed through the material in some other order or 60 series of steps than those shown and described without departing from the spirit of my invention.

I claim as my invention—

The improved method of staying a series of 65 worked button-holes, which consists in drawing a loop of thread, separate from the thread by which the button-holes are worked, up through the material at a point near the end and to one side of a hole, bending the loop to 70 the other side of the hole, drawing it down through the material on that side, then passing an end of the thread of which the loop is formed through the loop, and finally passing the free end of the thread to the successive 75 button-holes, staying each in the manner described.

STILLMAN A. WEST.

In presence of—

GEO. H. KNIGHT,
EDW. S. KNIGHT.
